UNITED STATES PATENT OFFICE

JOHN BYRON GOLDSBOROUGH, OF CROTON, NEW YORK, ASSIGNOR TO THE
PINNING COMPANY, OF NEW YORK, N. Y., A CORPORATION OF NEW

METHOD OF CONSTRUCTING PILES.

961,492.

Specification of Letters Patent. Patented June 14

Application filed July 6, 1909. Serial No. 506,055.

To all whom it may concern:

Be it known that I, JOHN BYRON GOLDSBOROUGH, a citizen of the United States, residing at Croton, in the county of Westchester and State of New York, have invented certain new and useful Improvements in Methods of Constructing Piles, of which the following is a full, clear, and exact specification.

10 My invention relates to an improvement in the construction of piles and is applicable to such piles as are intended to serve as an anchorage, as well as to those intended to serve as a support, being adapted both to piles that resist a longitudinal pull as to those that resist a similar thrust.

The particular kind of piles, in the construction of which my invention is used, is that formed of a fluid or semi-fluid composition which sets in position, and for which purpose, cement, grout, or concrete is well adapted and customarily used, although other compositions or material capable of compacting under pressure may be employed, as my invention does not reside in such composition, but in the method whereby the pile is formed. In the construction of such piles where they are intended to serve as a support or foundation, it is of great importance that the earth supporting the footing should be thoroughly consolidated and brought to a firm and uniform consistency, and it is also highly desirable that an enlarged footing should be constructed. The customary way of accomplishing these objects has been to excavate the earth for the lining of the pile and to enlarge the footing by excavating, as by a bucket, the use of a water jet, etc., and then 40 to insert the concrete and to compact the same by ramming where the pile is formed in place. This method compacts the concrete, but has little if any effect in increasing the compactness of the surrounding earth, and consequently will not materially enlarge the horizontal dimensions of the footing. This is due to the fact that the earth will not compact satisfactorily under the influence of a blow transmitted through 50 concrete, but it will under a continuing pressure applied in the same manner. The latter force will have a decided effect and has a capacity of compacting the earth to a great extent. The earth will assume a employed, acting

upon a piston to press the concrete and pact the earth. An effective force of hundred tons may be easily obtained by such jack, and assuming that the concrete is inserted through a pipe three feet in diameter, having an area of about ten square inches, this would give an effective pressure upon the concrete of ten tons to the square inch and will exert a continuous compressing force upon the earth at the footing of about one hundred and fifty pounds to the square inch. This will materially compress the earth and may be increased at will, either by increasing the power of the jack or jacks, or by decreasing the diameter of the column. It is a decided advantage to have the footing enlarged horizontally and not vertically. The ramming of the concrete by heavy blows, as I have stated, has only a slight compacting effect upon the earth, and this is liable to be transmitted in a vertical direction, as the concrete, not flowing quickly, will act more as a plunger and transmit the force of the blow to the earth directly beneath it. The earth, if of usual and substantially uniform density, will resist compression in a vertical direction to a much greater extent than it will in a horizontal direction, and this I assume to be due to horizontal stratification. Owing to this greater resistance, therefore, the effect of continuing pressure upon the concrete will convert the same into a semi-liquid or fluid piston, which will cause the earth to be compacted to a considerable extent horizontally, thereby enlarging the horizontal area of the footing, at the same time thoroughly compacting the surrounding earth in both horizontal and vertical directions, and filling any fissures or soft spots in the earth. The earth is thereby brought to a uniform and firm supporting condition. The additional important advantage, *i. e.*, the ultimate safe supporting power of the pile, due to the footing alone, and devoid of any assistance from skin friction, is easily obtained. For assuming that a column is designed to support a load of fifty tons, it is obvious that a pressure of one hundred tons is applied through the jack to compact the earth, that an eventual permanent load of fifty tons may be easily borne and leave ample margin of safety. In the construction of such concrete piles within the pile, the pile

is designed to carry the load. of withdrawing the casing and draw apart the concrete, and cause it to assume an irregular shape, occasionally to separate entirely. also, foreign material will fall into the concrete. These causes have disastrous results and instances n where structures have collapsed, the failure of the supporting col-tributable to such causes. I also see this difficulty, in cases where it is to withdraw the casing, by my d, by continuing the pressure upon the pipe while the pipe or casing is being drawn, whereby it is compacted and ed to compact the surrounding earth as the casing is withdrawn, and to fill the fissures and soft spots, and the intrusion of foreign material is entirely prevented, and the integrity and size of the pile maintained. constant or substantially constant pressure upon the concrete will, I believe, hasten the exclusion of the water and quicken the setting of the concrete and, also, owing to its compact structure, give it an increased supporting power.

Among the objects sought to be accomplished by my invention and some of the advantages achieved thereby are the following: To determine, by the method used in constructing such pile, the safe load which the same will bear. To enable the footing of a column to be increased in size if desired, and thereby to increase its supporting power or its resistance to displacement. To consolidate the earth at the footing of a column and thereby to increase its supporting power. To produce a pile wherein the concrete or other composition of which the same is composed shall not be separated or drawn apart by the withdrawal of the sheath wherein the same was formed, and from which foreign matter, such as earth, shall be excluded. To enable such composition pile to be reinforced where desired by the addition of metal rods or other strengthening members. To enable the earth surrounding such pile to be consolidated throughout a desired area and to any reasonable extent, whereby the friction between the pile and earth and the supporting power of the pile is increased, and whereby, also, any fissures or soft spots in the surrounding earth are strengthened. To determine in advance the size footing which will be required to construct the footing of such determined size. To permit the excavation for the footing of a pile to be made and its area and contour to be determined, free of any liability of earth or water to intrude and to permit the inspection thereof before excavation is finished.

Other objects which

invention consists in the method of constructing such piles whereby suitable pipe, tube, or cylindrical receptacles are located in the earth at the place to be occupied by said pile and preferably in a recess formed at the foot thereof, and the composition to be employed in the construction of the pile is then inserted and placed under continuous pressure, as, for instance, the pressure of a jack or other power device acting upon a piston, whereby the earth is slowly compressed and the opening for the footing enlarged.

My invention also consists in the method of constructing piles whereby a continuous pressure is exerted by mechanical means, as a piston upon the concrete, or other composition or material employed, in the manner described, as the said pipe or other lining is withdrawn, whereby the said composition is constantly under pressure and causes a consolidation of the surrounding earth and the filling of fissures and soft spots therein, and prevents the separation and disturbance of the said composition and the intrusion of foreign material, both of which frequently happen with disastrous results in the withdrawing of such linings as customarily practiced.

My invention also consists in the employment in such method of a flexible receptacle capable of being expanded and of consolidating the earth to a determined extent for the purpose of deciding the size of the opening for the footing and of permitting the same to be examined before it is filled, and which is particularly applicable in the case of soft earth.

In the employment of my method it is expected that the earth would yield horizontally and provide the enlarged horizontal base shown, but it is not essential that the enlarged portion shall be formed in the precise manner shown, since means are afforded to test the supporting power of the footing. The important fact is that by the use of my method the earth is brought to such a compact state that it will not yield further to a force applied which will be at least as great, and usually much greater, than the weight of the pile is designed to carry. Thereby the supporting power of the column is determined by the method of construction before the pile is completed.

The foregoing, as well as other matters of which my invention consists, are fully set forth in the following description, and they may be practically employed in the manner illustrated in the accompanying drawing, wherein—

Figure 1 illustrates a vertical section of a casing in which my improved pile is to be constructed, illustrating, also, the use of water jet to produce a preliminary enlargement of the foot.

2 illustrates an enlarged foot-
y my method, together with the
lities employed to enlarge the
3 is a view similar to Fig. 2,
g the employment of reinforcing
he concrete and the use of a weight-
orm as an abutment for the jack in
the building wall of Fig. 2. Fig. 4
ross-section on the line 4—4 of Fig. 3;
Fig. 5 illustrates the employment of a
ble bag to enlarge the footing.

the construction of piles by my method,
ite a casing in the earth at the point
e it is desired to construct the pile and
ferably drive the same to a depth sub-
stantially corresponding to the length of the
ile, excluding the footing which is con-
structed below the casing, and has a greater
horizontal area. Such casing may be sunk
in any approved manner, as, for instance, by
the employment of a hydraulic or other
powerful jack as 2, acting against a wall 3
of a building (Fig. 2), or a weighted plat-
form 4 (Fig. 3). Such method of sinking
the casing by pressure rather than blows,
possesses the great advantage that it does
not disturb adjacent structures, which is im-
portant, as such piles are frequently re-
quired to be formed adjacent to existing
buildings. The sinking of the casing by
pressure tends to consolidate surrounding
soil and actually to strengthen adjacent
foundations in cases where the soil is not re-
moved from the casing.

35 The earth within the casing may be re-
moved by suitable and well known means,
such as the pneumatic process, the use of a
water jet, an earth auger, etc., or the point
of the casing may be closed by a shoe or
40 plug, which is removable, and the soil is
compressed as the casing is driven, thereby
leaving the interior of the casing free of soil.

When the casing is free of solid matter,
the earth immediately below the casing is
45 preferably excavated, as by an orange-peel
bucket of the Hayward type, substantially
to the extent indicated at 5 (Fig. 1), and
this excavation may then be enlarged by
means of a water jet introduced through
50 pipe 6 having an end 7, bent substantially
horizontally, by means of which the excavation
is enlarged substantially to the dimen-
sions indicated by dotted lines (Figs. 1
and 2). A suitable quantity of concrete, ce-
55 ment, or other suitable composition 8, is
then inserted in the lower part of the casing,
filling the footing excavation as so enlarged,
and likewise the lower end of the casing. A
piston 9 is then inserted within the casing
60 and its head fits within the casing snugly
enough, so that the concrete will not escape
when pressure is applied, but the air will.
The piston may, if desired, be double-headed
as shown, in order that it may be guided
65 truly, or it may have a single head. A hy-

draulic or other powerful jac-
means of exerting continuing a
pressure is then arranged, so th
ert its force upon the piston an
ing wall 3, or a weighted platfor
used as an abutment for the jack.

The constant pressure of the
veying the power of the jack to ti
will cause the latter to act as a liqu
and to compact the earth effectua
all fissures and soft spots therein,
its greatest pressure in the direction
resistance of the earth, to wit, horizo
whereby, after the pressure has been
tained for a suitable period, the footing
be enlarged until it shall have assumed abou
the shape and size illustrated at 10 (Fig. 2),
or even larger if desired, and as the area of
the enlarged footing increases over the area
of the original excavation substantially as
the squares of the diameters, it follows that
a greatly increased bearing surface is ob-
tained.

It may be found desirable to employ a
follower 11, to interpose between the piston
and the jack in cases where headroom is lim-
ited or a deep casing is employed, as well
as when the concrete approaches the top
of the casing. The casing should be of su-
cient strength to resist the force of the jack,
although this is reinforced by the earth
backing.

In many instances it may be desired to
withdraw the casing for future use and to
facilitate this, chains and hooks 12, 13, are
provided, by means of which the casing may
be lifted in any of many ways. During such
withdrawing of the casing the pressure upon
the concrete may be continued, if desired,
or if not convenient, such pressure may be
applied intermittently so that the concrete
as released from the casing shall be thor-
oughly compacted and be brought into inti-
mate relation with the surrounding earth,
which will thereby also be thoroughly con-
solidated. Should any fissures or soft spots
in the earth be developed, they will be
thoroughly filled with concrete, and at the
withdrawal of the casing a positive assur-
ance is provided that the concrete pile is
at least as large as estimated and that its
integrity has not been impaired. The casing
has straight parallel sides as shown, and
thereby as it is withdrawn a snug fit is main-
tained with the surrounding soil and there
is no liability of the concrete flowing up the
side of the casing.

It is frequently desired to reinforce such
concrete piles and this may be easily accom-
plished by my method by the insertion of
rods 14, which pass through perforations 15
in the piston head and follower. Such rods
are extremely desirable in case the concrete
pile is to serve as an anchorage, and here
I prefer to make them with hooked ends

ed in Fig. 3. Such rods may prior to the introduction of the the footing may be further if desired, by the location lattice of rods. A going method will be found advantageous in the case of firm soil, gravel, or firm earth, but where is soft or heavily charged with modification thereof may be ad- ch as illustrated in Fig. 5. Here, formation of the preliminary foot- avation as above described has been ed, I insert within the casing a pipe aving a perforated flange 18, and a bag of suitable material, such as closely-woven canvas, is then secured to the pipe above the flange, as by band 20. This bag is collapsed when inserted, as shown by dotted lines. After insertion a piston 21, having a hollow rod and perforated head, fits over pipe 17, and will be lowered until its rests upon the bag to provide a backing for said bag. This piston head may, if desired, be provided with a packing 22. Instead of said piston the lower part of the casing may be filled with concrete which will, when set, provide sufficient backing for the bag. In such e the parts 17, 18, will remain in position and will provide a reinforcement for the mass. They should then be filled with grout or concrete. Piston 21 being in position, water is pumped into the bag 19 until it has been expanded to its fullest extent and assumes the desired size. This may be easily determined, for the capacity of the bag is known, as well as the quantity of water pumped in, and pressure upon the water is maintained until it has compacted and consolidated the earth and has assumed the desired size. The water may then be withdrawn by releasing the pressure and withdrawing the bag, and a quantity of liquid cement, as grout, introduced directly into the enlarged footing, the bag reintroduced, filled with water, pressure applied, and the grout pressed firmly around the walls of the excavation. When the grout has set in place, the bag may be withdrawn and the cement lining of the footing will then exclude surrounding water. The footing may, if desired, be thoroughly examined by the introduction of an electric lamp and if found suitable, concrete may be introduced, subjected to desired pressure, and the filling of the casing, and its withdrawal, if desired, proceeded with as hereinabove described.

The preliminary expanding of the excavation by means of the water-filled bag may be dispensed with and the grout introduced directly into the excavation as originally prepared, and pressed into place by the expansion of the water bag. In case the condition of the soil should be very soft, if de- ed the grout could be introduced in the

bag, thereby doing away with water, and expanded to place. I could not be withdrawn. In ver where the casing quickly fills w I may dispense with the excavati the pipe and proceed by lowering th the bottom of the casing, then fill grout, thereby displacing the water, applying pressure to the pipe, force grout to enlarge the bag to the desired extent to form a footing. This will also the foot of the casing against the fur ingress of water, whereupon the wat the casing may be pumped out and the filled as before, either withdrawing sa or not, as desired.

In the method above described, as well a in the modification thereof, the advantage is present that substantially the area of the footing may be known by the amount of concrete required. In both cases, also, the presence of the water at the base of the casing is not fatal to the construction of a substantial footing, as, while it is desirable to remove the water as far as possible by preliminary pumping, the force of the jack will tend to drive the water back into the soil and the balance will escape above the piston, permitting the concrete to set in a solid mass, as stated.

This method will be found highly desirable in the construction of piles in marshy land, where great difficulty is experienced, and it will also be advantageous in the construction of building piles, as well as in underpinning work, where it may be an advantageous adjunct to the Breuchaud method of underpinning. It will also be useful in constructing anchorages for the cables of suspension bridges.

What I claim is:

1. A method of forming piles, which consists in forming an opening in the soil, in then inserting a body of concrete or similar material at the foot thereof, and in then subjecting the said material to a continuing and uninterrupted pressure, determined by the load the pile is expected to carry, until the footing has been enlarged to the desired extent and has the requisite supporting power, substantially as described.

2. A method of forming piles, which consists in introducing a casing into the soil, in then inserting a body of concrete or similar material at the foot thereof, and in then subjecting the said material to a pressure substantially equal to the load the pile is eventually to carry, and continuing such pressure until the said footing presents a resistance to movement equal to such pressure, thereby consolidating the surrounding soil and ascertaining the supporting power of the pile, substantially as described.

3. A method of forming piles having an enlarged footing which consists in intro-

ducing a casing into the soil, in removing the soil from within said casing, in then inserting a body of concrete or similar material at the foot thereof, and in then subjecting 5 the said material to a pressure substantially equal to the load the pile is eventually to carry, until the footing has been enlarged to the desired extent, and continuing such pressure until the said footing presents a re-
 10 sistance to movement equal to such pressure, thereby consolidating the surrounding soil and ascertaining the supporting power of the footing, and in then adding additional material until the requisite length has been
 15 attained, and in subjecting the said material to continuous pressure at each addition thereto.

4. A method of forming piles, which consists in introducing a casing into the soil, 20 in then inserting a body of concrete or similar material at the foot thereof and applying continuous and uninterrupted pressure thereto determined by the load the pile is intended to carry, until the footing has been
 25 enlarged and compacted so that it will support said load without movement, and in then gradually filling the casing with said material and withdrawing the casing at each addition of said material and applying a
 30 continuing pressure to each additional charge of material until the pile is formed whereby the body of the pile is consolidated, substantially as described.

5. A method of forming piles having an enlarged footing, which consists in introducing a casing into the soil, in then introducing grout or similar material at the foot of the casing, in then introducing a flexible bag and filling the same with fluid material and applying continuous pressure thereto 35 until the footing has been enlarged, and maintaining the pressure until the grout has set, and in then filling the said excavation with concrete or similar material, substantially as described. 40

6. A method of forming piles, which consists in introducing a casing into the soil, in then removing the soil from within said casing, in then excavating at the foot thereof, in then introducing grout or similar cementing material within said excavation, in then inserting a flexible bag within said excavation, filling the same with fluid and applying pressure thereto, whereby the footing is enlarged to the desired extent and the 50 grout is distributed over the walls thereof, in maintaining such pressure until the grout sets, and in then withdrawing the bag and filling the footing and the casing with concrete or similar material, substantially as 55 described. 60
